UNITED STATES PATENT OFFICE

CHARLES W. WOODRUFF, OF COLUMBUS, OHIO

SYSTEM FOR MINIMIZING STATIC

Application filed January 31, 1928. Serial No. 250,840.

My invention relates to a system for minimizing the effect of static upon radio receiving devices.

The effects of static or atmospheric electricity is usually manifested in radio receiving apparatus by noises varying from hissing sounds to sharp crashes. The hissing and frying sounds usually have a normal volume which may be termed the normal static level, and the crashes are interspersed at various and indeterminate intervals depending upon atmospheric and other conditions.

An object of my invention is to devise a system for reducing the effect of atmospheric electricity upon the reception of radio signals, and in particular, to devise an arrangement in which the effect of the normal static level is rendered imperceptible and also the effect of the static crashes is reduced to an unobjectionable volume.

A further object of my invention, is to devise a system for reducing the effects of static upon radio reception without a substantial reduction in the volume of signal received.

My invention is illustrated in the accompanying drawing which is a schematic diagram of the circuit arrangement employed.

In the drawing, AN indicates an antenna for supplying received energy to a radio receiving set RS of usual construction employing vacuum tube relays and having a loud speaker LS connected thereto. The antenna AN is connected to one plate element P' of a double-wave rectifier tube RT. The filament F of the rectifier tube RT is energized from the A battery of the radio set RS as shown. The second plate element P² is connected to the antenna terminal *a* of the radio set and the ground terminal *b* is grounded at GN in the usual manner. The A battery is grounded in the usual manner through the ground terminal as indicated in dotted line. The antenna AN is also connected to the variable arm of a three-point tap switch TS. The contact 1 of tap switch TS is connected to the variable arm of static minimizer cell M. The contact 2 is connected to one terminal of a variable resistance R, and contact 3 is connected to one terminal

of a variable condenser C. The remaining terminals of the elements M, R and C are joined together and connected to the antenna terminal *a* of the set RS. The minimizer M is constructed in accordance with the disclosure in my copending application Ser. No. 6,813, filed September 4, 1925. It consists of a number of electrolytic cells connected in series, each cell comprising a container filled with electrolyte and provided with suitable electrodes. For example, the electrolyte may be a solution of ammonia phosphate and the electrodes may be lead and aluminum or both of aluminum. Connections are made from between each cell to points on a tap switch in order that the number of cells included in the circuit may be varied.

In the operation of my invention, I have found that the arrangement shown will operate satisfactorily to reduce the effect of static disturbances without any of the elements M, R and C connected in the circuit. In other words, satisfactory operation of the system may be obtained with the arm of tap switch TS placed in a position out of contact with any of its contact points. In this condition the operation is believed to be as follows: The incoming current supplied by the antenna is impressed upon the plate P¹ of the rectifier tube RT and the positive alternations of the wave as well as the positive portions of the static interference are conducted to ground by way of the rectifier path between the filament F and the plate P¹, that is, this path serves to conduct at least a portion of the energy of the positive portions of the wave to ground. Undoubtedly the natural capacity existing between the plate elements P¹ and P², which is indicated at C¹, is effective in transferring or affording a path for the high frequency current from the antenna to the antenna terminal *a* of the receiving set. The filament F and the plate P² also constitute a rectifying element connected between the antenna terminal of the set and the ground, and functions in a manner similar to the rectifying element referred to above. It is obvious that the negative alternations are not conducted to ground through either of the rectifying elements. I do not

attempt to explain here the exact theory of operation of my invention and I do not intend to be bound by any theory which might be set forth, but I have experimentally demonstrated the fact that the arrangement connected as shown is effective in substantially reducing the effect of static upon the radio reception.

When operated as described above, the effect of the static is satisfactorily reduced somewhat at the expense of the volume of reception. I find that the volume may be brought up to a satisfactory value by connecting the minimizer M between the antenna and the antenna terminal of the set, as by means of the tap switch TS. The minimizer M is effective not only in reducing the effect of static upon the reception, in addition to the operation of the rectifier tube RF, but it serves to increase the volume of reception. The action of these two elements appears to be complementary, that is, one element appears to be operative to reduce the effects of static where the other element is deficient in its operation. It will be noted that the filament F and the plate P¹ of the rectifier tube constitute a rectifier element connected between one terminal of the minimizer M and the ground, and the filament in combination with plate P² constitute a second rectifier path connected between the other terminal of minimizer and the ground. It is believed that the first rectifier path is effective in reducing both the normal static level and the static crashes to a minimum and the second rectifier path serves to effectively reduce such amounts of static as are transmitted through the minimizer M. The action of the cell is such that large impulses or crashes above a predetermined intensity causes a marked increase in the resistance of the cell practically simultaneously with the impulses, while only a small increase of resistance is caused by signals below this intensity.

I find that satisfactory operation with increased volume may also be obtained by substituting for the minimizer M a variable resistance R, or a variable condenser C. This may be done by changing the position of the arm of tap switch TS to include the desired element in the circuit.

It is obvious that instead of incorporating both rectifier paths into a single tube element, separate two-element tubes may be employed for each path.

While I have shown one form of my invention for the purpose of explanation, it is obvious that the details may be varied without departing from the essence of the invention.

What I claim is:

1. In combination, an antenna, a radio receiving set provided with antenna and ground terminals, a double-plate thermionic rectifier including an electron emitting cath-

ode, said antenna being connected to one plate of the rectifier and the other plate being connected to the antenna terminal of the receiving set, and a path from the cathode of the rectifier to ground.

2. In combination, an antenna, a radio receiving set provided with antenna and ground terminals and an energizing battery connected to said ground terminal, a rectifier tube comprising a filament and two plate elements cooperating therewith, a circuit for energizing the filament from the said battery, said antenna being connected to one plate element, and the other plate element being connected to the antenna terminal of the receiving set.

3. In combination, an antenna, a radio receiving set provided with antenna and ground terminals, a double-plate thermionic rectifier including an electron emitting cathode, said antenna being connected to one plate of the rectifier and the other plate being connected to the antenna terminal of the receiving set, an impedance element connected between the two plate elements of the rectifier, and a path from the cathode of the rectifier to ground.

4. In combination, an antenna, a radio receiving set provided with thermionic relays and antenna and ground terminals, an energizing battery for said relays connected to ground through said ground terminal, a rectifier tube comprising a filament and two plate elements cooperating therewith, a circuit for energizing the filament from the said battery, said antenna being connected to one plate element, and the other plate element being connected to the antenna terminal of the receiving set.

5. In combination, an antenna, a radio receiving set provided with antenna and ground terminals, a double-plate thermionic rectifier including an electron emitting cathode, said antenna being connected to one plate of the rectifier and the other plate being connected to the antenna terminal of the receiving set, a static reducing element connected between the two plate elements of the rectifier, and a path from the cathode of the rectifier to ground.

6. In combination, an antenna, a radio receiving set provided with thermionic relays and antenna and ground terminals, an energizing battery for said relays connected to ground through said ground terminal, a rectifier tube comprising a filament and two plate elements cooperating therewith, a circuit for energizing the filament from the said battery, said antenna being connected to one plate element, the other plate element being connected to the antenna terminal of the receiving set, and an impedance element connected between said plate elements.

7. In combination, an antenna, a radio receiving set, an antenna circuit extending

from the antenna to ground and including the receiving set and an impedance element between the antenna and the set, an asymmetrically conducting path connected between the antenna and ground, and a second asymmetrically conducting path connected between the input terminal of the set and ground.

5 8. In combination, an antenna, a radio receiving set, an antenna circuit including the receiving set and a static reducing element connected in said circuit between the antenna and the set, and an asymmetrically conducting path connected from one terminal of said element to ground.

10 9. In combination, an antenna, a radio receiving set, an antenna circuit extending from the antenna to the ground through said receiving set, an electrolytic cell connected in said circuit between the antenna and the receiving set, and an asymmetrically conducting path connected between the antenna and ground.

15 10. In combination, an antenna, a radio receiving set, an antenna circuit extending from the antenna to the ground through said receiving set, a resistance connected in said circuit between the antenna and the receiving set, and an asymmetrically conducting path connected between the antenna and ground, and a second asymmetrically conducting path connected between the antenna terminal of the set and ground.

20 11. In combination, an antenna, a radio receiving set, an antenna circuit extending from the antenna to the ground through said receiving set, a condenser connected in said circuit between the antenna and the receiving set, and an asymmetrically conducting path connected between the antenna and ground, and a second asymmetrically conducting path connected between the antenna terminal of the set and ground.

25 40 In testimony whereof I have hereunto signed my name.

45 CHARLES W. WOODRUFF.
